UNITED STATES PATENT OFFICE.

JAMES R. HARRISON, OF PEORIA, ILLINOIS.

CATCH-BASIN OR SEWER-INLET.

1,239,102.

Specification of Letters Patent. Patented Sept. 4, 1917.

Application filed September 14, 1916. Serial No. 120,021.

To all whom it may concern:

Be it known that I, JAMES R. HARRISON, a citizen of the United States, residing at Peoria, in the county of Peoria and State of Illinois, have invented new and useful Improvements in Catch-Basins or Sewer-Inlets, of which the following is a specification.

This invention has reference to improvements in catch-basins or sewer-inlets.

The object of the present invention is to improve catch-basins of that type shown in the patent granted to George A. Ensign, April 7, 1896, No. 557,786, by providing an attachment for such a basin which is designed to prevent all gases and foul odors from ascending or passing upwardly through the same, and yet which is so constructed as will permit waste water to pass freely through said basin into a sewer pipe connected thereto.

Catch-basins of the type shown in the Ensign patent and basins of similar construction are in use in a great many localities throughout the country, but the one serious objection to them is that, no provision is made for preventing the escape of the gases and foul odors which frequently rise from the sewer and pass out through the catch-basin, endangering the health of the residents residing in the vicinity of location of such basins, to say nothing of the unpleasantness occasioned by the escape of such odors from these basins. With my attachment all these objections are overcome, and at a small expense sanitary living conditions may prevail by the use of these basins.

More particularly, my invention comprises a preferably cast-ring adapted to be placed down in the neck or conical collar of the basin; a weighted plate having a pivotal connection with said ring, said plate adapted to be opened by the weight of the water entering said basin and to automatically close when the water has passed into the sewer pipe connected to said basin, and an arched plate or member connected to opposite sides of the ring, by means of which the attachment may be placed into or removed from the catch-basin, and which will limit the movement of the plate when it reaches its full open position. This arched plate is also preferably provided with an extension leading into the mouth of the catch-basin to divide trash entering the basin with the waste water.

In the drawings:—

Figure 1 is a partial vertical sectional view of a catch-basin of the "Ensign" type with my attachment applied thereto.

60

Fig. 2 is a perspective view of my attachment, with the valve plate in an open position, and

Fig. 3 is a detail sectional view showing the preferred connection between the ring, 65 valve plate and arched plate.

In the drawings, like characters of reference denote corresponding parts throughout the figures.

The catch-basin includes the body A 70 formed with the opening B providing a mouth through which the waste-water enters the basin leading to the sewer, and having a flange or flanges C by means of which the basin is attached to its support. Depending 75 from the body A of the basin is a conical collar or neck D which leads to and to which the sewer-pipe (not shown) is connected. At the opening of the mouth B of the basin is a grating E, and F is the cover for the 80 basin.

Referring now to my attachment, 1 designates preferably a cast-ring having the sloping surface 2 leading to the opening 3 of the ring. This ring 1 is preferably of a smaller 85 diameter than the inner circumference of the body A of the basin to permit the easy placing of the ring in the basin and removal therefrom, and when in the basin, the ring will rest preferably on the wall of the 90 neck or collar D of the basin below the plane of the flange or flanges C. It is also preferable when using the attachment with a type of basin illustrated, to incline the peripheral edge of the ring, as at 4, to provide 95 a reasonably true fit between the ring 1 and the neck or collar D of the basin, whereby there is no opening left between these parts.

At opposite points and off center, said ring 1, is provided with depressed bearings 6, 100 see Fig. 3, in which may be journaled trunnions 7 connected with a valve plate 8. The cap-plates for covering the trunnions and forming a complete bearing for the same, are designated 9, and are preferably cast integral with legs 10 of an arched plate 11, the cap plates of the arched plate 11 being bolted or otherwise suitably secured to the ring 1. The arched plate 11 is of such a height as not to interfere with the cover F 110 of the basin, when it is in place, and one side of the arched plate 11 is preferably ex-

tended, as at 12 which projects into the mouth of the basin for the purpose of dividing any trash which may enter the basin with waste water. The extension of said 5 arched plate and the plate itself serves as a protector or shield for the valve plate when open, and is engaged by the valve plate when in open position to limit the swing of said plate.

10 The valve plate 8 has the weighted portion 13, formed on or attached to the underside thereof, which serves to normally hold the valve plate in the closed position shown in full lines in Fig. 1, and said valve plate 15 is provided with a lug extension 5 adapted to engage with the ring 1 when it is swung to its closed position.

The trunnions 7 on the valve plate 8 are 20 preferably located off center of said plate, the weight 13 serving to balance the plate and return it to its closed position after the operation of opening the valve, caused by the waste water passing into and through the basin. The water entering the basin 25 and falling upon the unweighted part of the valve plate will swing the valve into the open position shown in dotted lines in said Fig. 1.

It is obvious that I have provided an 30 exceedingly practical and simple attachment of the character referred to, which may be manufactured at the lowest possible cost, and which may be applied to basins, in construction, similar to the one illustrated without any change in the construction of said 35 basin; also, that the attachment is adaptable to other and similar basins.

What I claim is:—

1. An attachment for catch-basins of the 40 character described, comprising a ring-like member, said member having trunnion seats, a weighted plate having oppositely located trunnions adapted to have a bearing in the trunnion seats in said ring-like member, and 45 an arched member, said member having cap-plates adapted to be attached to said ring-like member and cover said trunnions.

2. An attachment for catch-basins of the 50 character described, comprising a ring-like member, said member having trunnion seats,

a weighted plate having oppositely located trunnions adapted to have a bearing in the trunnion seats in said ring-like-member and also provided with a lug adapted to engage with said ring-like-member when said plate 55 is in a closed position, cap-plates for the trunnions adapted to be secured to said ring-like-member, and an arched member connected to said cap plates, said arched member adapted to serve as a stop for said 60 weighted plate when swung into open position.

3. An attachment for catch basins of the character described, comprising a ring-like-member, a valve plate having a pivotal connection with said ring-like-member and provided with a lug adapted to engage with said ring-like-member when said plate is in a closed position, and an arched member connected to the opposite sides of said ring-like-member, said arched member adapted to 70 serve as a stop for said weighted plate when swung into open position.

4. An attachment for a catch basin having a mouth portion and a depending neck or collar, comprising a ring-like-member adapted to rest within said neck or collar of the basin, a valve plate having a pivotal connection with said ring-like-member, and an arched member connected to the opposite 80 sides of said ring-like-member, said arched member having an extension on one side of which is adapted to extend into the mouth of the basin to divide any trash entering the basin with the waste water and to form a 85 stop for said valve plate when in open position.

5. An attachment for catch basins of the character described, comprising a ring-like-member provided off center with oppositely 90 located depressions, a valve plate, trunnions located off center and on the opposite sides of said valve plate, said trunnions adapted to have a journal bearing in the depressions in said ring-like-member, a weight attached to said valve plate, and an arched member connected to opposite sides of said ring-like-member. 95

JAMES R. HARRISON.
